UNITED STATES PATENT OFFICE.

BENJAMIN SKIDMORE, JR., OF CHICAGO, ILLINOIS.

SUCTION-CREATING APPARATUS.

1,409,315.

Specification of Letters Patent. Patented Mar. 14, 1922.

Application filed March 27, 1919. Serial No. 285,487.

To all whom it may concern:

Be it known that I, BENJAMIN SKIDMORE, Jr., a citizen of the United States, residing at Chicago, in the county of Cook and State 5 of Illinois, have invented certain new and useful Improvements in Suction-Creating Apparatus, of which the following is a specification.

This invention relates to improvements in 10 suction creating apparatus and one of the objects of the invention is to provide an improved apparatus of this character embodying an impeller having provisions for displacing a fluid and which displacement of the 15 fluid operates to create a suction upon another fluid confined in a chamber or conduit, the apparatus being also provided with one or more volutes into which the displaced liquid is delivered by the impeller and the 20 movement of the liquid in and through the volutes will operate to cause additional or further displacement or suction upon the fluid in the chamber or conduit.

To the attainment of these ends and the 25 accomplishment of other new and useful objects as will appear, the invention consists in the features of novelty in substantially the construction, combination and arrangement of the several parts hereinafter more 30 fully described and claimed and shown in the accompanying drawings illustrating this invention and in which—

Figure 1 is a vertical sectional view of an 35 improved apparatus of this character constructed in accordance with the principles of this invention and as taken on line 1—1, Figure 2.

Figure 2 is a vertical sectional view as taken on line 2—2, Figure 1.

Figure 3 is a view similar to Figure 1 showing the parts in another position.

Referring more particularly to the drawings the numeral 10 designates a tank or receptacle in which the apparatus may be located and is provided with a discharge outlet passage 11 for the fluid, and in which passage may be arranged a controlling valve 12.

The tank or receptacle 10 may be of any 50 desired size and configuration and supported in any suitable manner such as by means of legs 13.

Arranged within the tank is a casing designated generally by the reference numeral 55 14. This casing is provided with an inlet 15 by means of which the liquid in the tank

will flow into the casing, and the casing is also provided with a discharge outlet designated generally by the reference number 16 and which discharge outlet is also disposed 60 within the tank and at a point above the normal liquid level.

Arranged within the casing 14 is a rotary impeller 17 which is connected with a shaft 18, the latter having a bearing 19 in one wall 65 of the tank and having its extremity journaled in another bearing 20 supported by the opposite wall of the tank. This shaft 18 is adapted to be rotated in any suitable manner such as by means of a motor 21 so that 70 when the shaft 18 is rotated the impeller 17 will also be rotated. The impeller is provided with a fluid passage therethrough which communicates with the inlet 15. This fluid passage may be arranged in any suitable manner but is here preferably shown as comprising two branches 22 which radiate from the axis of rotation and the passages are preferably curved from the axis towards the periphery of the impeller and in a direction 75 so that the passages will discharge or displace the liquid in the same general direction as the direction or rotation of the impeller so that the velocity of the liquid discharged will be substantially equal to the 80 peripheral speed of the impeller. This particular arrangement of the passages, however, may be varied.

The casing 14 is provided with a series of volute shaped passages 23—24—25 which merge into the discharge outlet 16, and an additional volute passage 26 may be provided which has communication with the casing and which latter passage is provided with a discharge outlet 27 located above the normal liquid level in 95 the tank, so that when the impeller is rotated the liquid in the tank flowing into the casing through the opening 15 will be directed into the impeller 17 at the center and will flow through the branches 22 of the passage through the impeller to be discharged by the impeller through its periphery as the impeller rotates.

The liquid thus discharged or displaced by the impeller will be delivered intermittently and successively into the volute passages 23—24—25—26 inasmuch as the inlets of these respective passages are arranged along the line of travel of the impeller. After the liquid has been thus delivered into 110 these volute passages it will flow through the passages and be delivered into the tank.

The casing 14 is provided with a series of ports or openings 28—29—30—31, through the wall thereof and an annular ring or cup-shaped element 32 is provided to cover and 5 connect these ports. The ports preferably extend through the wall of the tank and the element 32 is located on the outside of the tank, although the position and arrangement of these ports and the element 32 may 10 be varied. A conduit 33 has communication with the chamber formed by the element 32 and in which conduit a suction is created by the displacement of the liquid by the impeller. The operation of this portion 15 of the mechanism is as follows: When the liquid is displaced by the impeller, that is, when it is discharged through the passages 22 into the respective volute shaped passages 23—24—25—26, as the liquid flows 20 past the ports 28, 29, 30, 31, a suction will be created in the conduit 33. As the impeller continues to rotate the discharge passages 22 will be cut off or moved out of communication with the respective volute passages, 25 so that the liquid flowing through the volute passages after the discharge from the impeller has been cut off, by reason of the momentum of the liquid in the passage, and inasmuch as the port is connected with the 30 passage, will create an additional or further suction which will be manifested in the conduit 33.

While the preferred forms of the invention have been herein shown and described 35 it is to be understood that various changes may be made in the details of construction and in the combination and arrangement of the several parts within the scope of the claims without departing from the spirit of 40 this invention.

What is claimed as new is:

1. An apparatus of the character described embodying a casing having a liquid inlet, and a rotary impeller within the casing, said impeller having a liquid passage therethrough, said casing embodying one or more volute shaped passages for the liquid, there being a fluid conduit having communication with the casing whereby 50 when the liquid is discharged by the impeller into the volute passage, a suction will be created in the said fluid passage and the movement of the liquid through the volute passage will create additional suction in the 55 fluid passage.

2. An apparatus of the character described embodying a chamber, an impeller in the chamber, one or more volute shaped passages having inlets arranged along the 60 path of movement of the impeller to receive

the liquid discharged by the impeller, and a conduit having communication with the said passages whereby the delivery of the liquid by the impeller into the said volute shaped passages past the point of communication of the conduit and passages will create suction in the conduit, the movement of the liquid through the said volute shaped passages creating additional suction in the conduit.

65

70

3. An apparatus of the character described embodying a rotary impeller, a plurality of volute shaped passages having their inlets arranged in close proximity to and along the path of movement of the impeller whereby the liquid displaced by the impeller will be discharged into the said passages, and a fluid conduit having communication with the passages whereby the liquid delivered into the passages will create a suction in the conduit, the kinetic energy of the liquid in the said passages after the impeller ceases to deliver liquid thereinto operating to create additional suction in the said passages.

80

85

4. An apparatus of the character described embodying a rotary impeller, a plurality of volute shaped passages having their inlets arranged in close proximity to and along the path of movement of the impeller whereby the liquid displaced by the impeller will be discharged intermittently and successively into the said passages, and a fluid conduit having communication with the passages whereby the liquid delivered 90 into the passages will create a suction in the conduit, the kinetic energy of the liquid in the said passages after the impeller ceases to deliver liquid thereinto operating to create additional suction in the said passages.

95

100

5. An apparatus of the character described embodying a rotary impeller, having a liquid passage therein, a volute shaped passage having its inlet adjacent the path of movement of the impeller to receive from the impeller the liquid displaced thereby, a fluid passage, and means whereby the displacement of the liquid by the impeller will create a suction in the said fluid passage, the said means embodying provisions whereby the delivery of the liquid into the volute shaped passage will be intermittent while the suction manifested in the fluid passage through the volute shaped passage remains 110 constant.
